UNITED STATES PATENT OFFICE.

EDWARD P. CARLSON, OF SEATTLE, WASHINGTON.

VALVE.

1,202,670.

Specification of Letters Patent. Patented Oct. 24, 1916.

Application filed July 26, 1915. Serial No. 41,850.

To all whom it may concern:

Be it known that I, EDWARD P. CARLSON, citizen of the United States, residing at Seattle, in the county of King and State of Washington, have invented a certain new and useful Improvement in Valves, of which the following is a specification.

My invention relates to improvements in valves for controlling the flow of fluid through conduit pipes, and the object of my improvement is to provide a valve whose passageway may be opened by a manual actuation of some of the operative parts and be closed automatically by other of its operative parts in response to the action of the fluid to which such other parts are subjected, or, whose said passageway, after being so opened may be maintained open, if it be so desired, by the manual adjustment of another of its parts; and a further object of my improvement is to provide a valve whose movable parts may be actuated without the aid of any spring and which shall be durable and reliably efficient in its operation. I accomplish this object by devices illustrated in the accompanying drawings wherein I have shown my invention as embodied in a faucet which is adapted for use in connection with water supply pipes associated with stationary wash-basins, wash-tubs, bath-tubs and the like, and in which drawings—

Figure 1 is a view of such faucet showing its principal parts in vertical mid-section; Fig. 2 is a view of the same in horizontal section on broken line z , z of Fig. 1; Fig. 3 is a view of the same in horizontal section on broken line y , y of Fig. 1; and Fig. 4 is a fragmentary view of the same on broken line z , z of Fig. 1.

Referring to the drawings, throughout which like reference numerals indicate like parts, a tubular base portion 5 is provided with a downwardly extended nipple 6, by which the faucet may be secured to a support and connected to a water supply pipe, and is further provided with an external screw-thread around its upper end portion, while the inner side of its circular wall is provided with a plurality of vertical grooves 7.

Within the tubular base portion 5 is loosely disposed a cylindrically formed hollow metal float 8 whose buoyancy adapts it to rise to its position shown in Fig. 1 in response to the presence of water in said base portion 5, which water may find passage

ways through said grooves 7 to the space above said float 8. Screwed onto the screw-threaded upper end portion of said base portion 5 is the internally screw-threaded flange 9 of a hollow metal body portion 10 whose bottom wall 11 is provided with a concentrically disposed passageway that extends upwardly through it and through a sleeve 12 which is integral therewith, said passageway being countersunk in its lower end to provide a seat for a puppet valve 13 removably disposed therein, said puppet valve 13 being integrally attached to a valve spindle 14 which extends upwardly through the sleeve 12 into the space thereabove.

The valve-spindle 14 is provided with a plurality of grooves 15 (as shown more clearly in Fig. 4) which extend from the puppet valve 13 to its top end whereby water may flow upwardly through the sleeve 12 if the puppet valve 13 be moved downwardly from its seat in response to pressure exerted on the top end of the valve-spindle 14.

Extending downwardly from the bottom of the puppet valve 13 is a boss 16 against the bottom end of which the top side of the float 8 engages to exert a pressure that tends to maintain said puppet valve 13 in its closed position.

The top wall of the body portion 10 is provided with a concentrically disposed hole that extends upwardly through it and the side surface of said hole at a point near its bottom end is provided with a circumferential groove 17, and such hole is further provided with a slot 18 that extends vertically throughout its length, and within said hole is slidably disposed a plunger 19 whose bottom end surface is engaged by the end surface of the valve-spindle 14.

The plunger 19 extends upwardly for a distance above the top of the body portion 10 to engage with a lever 20, one end of which is articulated with an arm 21 which is integrally attached to said body portion 10 whereby when said lever 20 is depressed by pressure exerted on a knob 22 attached to its free end, the spindle-valve 14 will be moved downwardly to open the puppet valve 13.

The plunger 19 is provided with an outwardly projecting pin 23 which engages with the vertical sides of the slot 18 and which is disposed to engage with the upper side of the circumferential slot 17 in re-

sponse to a rotary movement of said plunger 19 when said plunger 19 is depressed to move said pin 23 downwardly to a point where it registers with said circumferential 5 slot 17, thus to lock said plunger 19 in such position that the puppet valve 13 will be opened to permit water to pass upwardly through the grooves 15 formed in the valve- stem 14; and such rotary movement of said 10 plunger 19 may be effected by turning a milled nut 24 fixed on the upper end of said plunger 19.

The top of the body portion 10 is provided with an upwardly projecting screw- 15 threaded flange 25 upon which is disposed a screw-threaded flanged collar 26 which serves to confine a suitable packing that may engage with the circumferential surface of the plunger 19 to prevent a leakage 20 of water from the interior space within the body portion 10.

A curved nozzle 27 is screwed into a screw-threaded hole disposed in the side wall of the body portion 10 to extend therethrough thus to permit water to escape from the interior space of said body portion 10.

The operation of the faucet, thus illustrated and described is as follows: The nipple 6 being attached to a water supply pipe, in a well known manner, water will enter the space within the base portion 5 with the result that the float 8, by its buoyancy, will raise the valve-spindle 14 to cause the puppet valve 13 to close the passageway through the sleeve 12 and the groove 15 and to cause the plunger 19 to rise and lift the lever 20 to its normal position, as indicated in Fig. 1, the force of such buoyancy of the float 8 being aided by the 30 impact or pressure of such water, and after the puppet valve 13 is thus closed, then the buoyancy of the float 8 alone will be sufficient to maintain the puppet valve 13 closed. Then, if it be desired to draw water 35 from the nozzle 27, the knob 22 must be depressed to cause the lever 20 to force the plunger 19 downwardly to open the puppet valve 13, in an obvious manner, and such knob 22 may be maintained in a depressed 40 position until a sufficient amount of water has been obtained from the nozzle 27, whereupon the knob 22 may be released to permit the float 8 and the pressure of water on the puppet valve 13 automatically to actuate 45 the puppet valve 13 to move upwardly to close the passageway through the sleeve 12 and the grooves 15. If, however, it be desired to lock the puppet valve 13 in its wide 50 open position to permit water from the 55 nozzle 27 to flow continuously, then in such case, when the plunger 19 has been depressed to that position where the pin 23 registers with the circumferential slot 17,

the milled nut 24 is turned to rotatively move said plunger 19 to cause said pin 23 65 to enter the circumferential slot 17 thus to prevent an upward movement of said plunger 19, in a well known manner. After water has flowed continuously through the nozzle 27 for a required length of time then 70 the milled nut 24 is turned to rotatively move the plunger 19 until the pin 23 registers with the vertical slot 18 whereupon the plunger 19 will be permitted to rise in response to pressure exerted through the 75 valve-spindle 14.

If it be desired, the pin 23 in the plunger 19 and the vertical slot 18, together with the circumferential slot 17 may be dispensed with, in which case, the said plunger 80 19 cannot be locked in a position to maintain the puppet valve 13 open.

Manifestly, changes may be made in the forms, dimensions and arrangement of parts of my invention without departing 85 from the spirit thereof.

What I claim is:

In a valve of the class described the combination with a tubular member having an enlarged chamber at its upper end and 90 having its lower end portion adapted to be attached to a fluid-supply pipe, the enlarged chamber being provided with longitudinal channels in its walls, of a buoyant member fitted within said enlarged chamber with 95 the periphery thereof engaging the inside wall of the enlarged chamber and slidably therein, the said channels forming passages disposed in spaced relation around the buoyant member, a hollow body member 100 having a hole through its top wall and disposed with its bottom wall covering the top end of said tubular member and secured thereto, said bottom wall having an upstanding nipple with a passageway extending upwardly therethrough; a puppet valve carrying an integral depending lug disposed to engage with said buoyant member and adapted to open and close said passageway 110 in response to its vertical movements; a plunger disposed to be slidably movable within said hole in said top wall of said body member and adapted to engage with said puppet valve whereby said puppet valve may be disposed to open said passageway in response to a downward movement of said plunger; and a delivery pipe 115 disposed to conduct fluid from the space within said body member.

In witness whereof, I hereunto subscribe 120 my name this sixth day of July, A. D. 1915.

EDWARD P. CARLSON.

Witnesses:

O. JOHNSON,
A. HASKINS.
